DESIGN FOR A BOTTLE

Charles Davis Little, Chattanooga, Tenn., assignor to Seminole Flavor Company, Chattanooga, Tenn., a corporation of Tennessee

Application December 19, 1936, Serial No. 66,640

Term of patent 14 years

To all whom it may concern:

Be it known that I, Charles Davis Little, a citizen of the United States, residing at Chattanooga, in the county of Hamilton and State of Tennessee, have invented a new, original, and ornamental Design for a Bottle, of which the following is a specification, reference being had to the accompanying drawing, forming a part thereof.

In the drawing,

The figure is a side view in elevation of a bottle, showing my new design. The bottle as shown is round and its opposite side, not shown, is substantially the same in appearance as the side shown, differing only in that the hoop joints appear on the three lower hoops.

I claim:

The ornamental design for a bottle, substantially as shown and described.

CHARLES DAVIS LITTLE.
